BRASSIÈRE

Jack Glick, Bronx, N. Y., assignor to The Gluckin Corporation, New York, N. Y., a corporation of New York

Application April 3, 1946, Serial No. 659,334

3 Claims. (Cl. 2—42)

1

This invention relates to brassières. More particularly, the invention deals with a back strap or elastic strap coupling between rear end portions of a brassière in adjustably and yieldably supporting the brassière upon the body of the wearer. Still more particularly, the invention deals with coupling straps or elastics of V-shaped contour adapted to interfit one with respect to the other and to more firmly maintain proper position of the brassière upon the body of the wearer. The novel features of the invention will be best understood from the following description when taken together with the accompanying drawing, in which certain embodiments of the invention are disclosed, and in which the separate parts are designated by suitable reference characters in each of the views; and in which:

Fig. 1 is a front perspective view of a brassière made according to my invention.

Fig. 2 is a rear view of the brassière on an enlarged scale, showing only the central portion thereof and with parts in a turned back position; and

Fig. 3 is a partial section on the line 3—3 of Fig. 2, on an enlarged scale.

While my present back strap construction is applicable to brassières having any type or kind of pocket construction, for illustrative purposes, I have shown the same applied to a brassière of the type and kind disclosed in my prior Patent 2,337,810 of December 28, 1943.

In Fig. 1, the brassière 10 comprises front pocket portions 11 and 12, each formed of upper portions 13 and 14 to which is attached a lower band portion 15 joining the pockets centrally of the front of the garment. The upper portions 13 and 14 of the pockets have strap extensions 16 and 17, respectively, which cross centrally of the garment, as seen at 18. The straps terminate in elastic ends 19 and 20 attached to the side seams 21 and 22. Extending from the seams 21 and 22, are side and back bands 23 and 24 having inturned reinforced edges 25 and 26.

The straps 16 and 17 are adapted to firmly support the upper portions 13 and 14 upon the breasts of a wearer and to accomplish this yieldably through the elastics 19 and 20. Attached to the upper ends of the pockets or the parts 13 and 14, are shoulder straps 27 and 28, the forward ends having elastic inserts 29 and 30 to yieldably support the pockets from the shoulders of the wearer.

In Fig. 2 of the drawing I have shown the rear end portions of the side bands 23 and 24, to the central portions of which are secured strips 31 and 32, which in turn each support a plurality

2

of longitudinally spaced eyes 33 and 34. These eyes provide means for adjustably coupling back straps 35 and 36 therewith in adjustably supporting the brassière about the body of the wearer.

5 The straps 35 and 36 each comprise a pair of elastic straps converging to their free ends 37 and 38. To the ends 37 and 38 are secured hook members 39 and 40 adapted to engage the eyes 34—33, respectively. The other diverging ends 10 of the strap members 35 and 36 are secured to the reinforced ends 25 and 26, as will clearly appear from a consideration of Fig. 2 of the drawing.

The strap members 35 and 36 may be composed 15 of elastic or non-elastic material, elastic material being preferably employed from the standpoint of yieldable support of the brassière about the body of the wearer, notwithstanding adjustments made in attachment of the hooks 39 and 40 with the eyes 34 and 33. It will also appear from a consideration of Fig. 2 of the drawing that the converging end of one strap member passes through the opening formed by the V-shaped contour of the other strap member and either end may be 20 so arranged with respect to the companion strap member.

In Fig. 2 of the drawing, the end 37 of the strap 35 is shown as extending outwardly through the opening 41 of the strap member 36, the two 25 strap members 35 and 36 overlapping centrally of the back of the brassière. This construction provides free relative movement of the V-shaped strap members one with respect to the other, particularly in compensating for expansion and contraction of the body of the wearer.

35 It will appear that the strap members 35 and 36 each extend from upper and lower edge portions of the bands 23 and 24 and couple centrally with the opposed bands. Thus it will be apparent 40 that the bands 23 and 24 will be maintained in flat relationship to each other upon the body of the wearer and gathering of these band ends is obviated. Furthermore, a pull of the shoulder straps upon the ends 23 and 24 will also be taken 45 up to some extent by the strap members 35 and 36, thereby operating to maintain position of the brassière upon the body of the wearer. In other words, a brassière employing the back strap construction herein disclosed will be firmly and yet 50 yieldably supported upon the body of the wearer.

Considering Fig. 3 of the drawing, it will appear that the strips 31 and 32, or the mounting of the eyes 33—34 thereof is reinforced by a strip folded over and partially covering the eyes, the strip 32 55 only being shown in Fig. 3, but it will be apparent

that the strip 31 is similarly constructed. In Fig. 3 I have shown at 42 a supplemental strip having the portions 43 which overlie and cover part of the eyes 34.

In Fig. 1 of the drawing I have indicated at 43' one of these overlying and reinforcing portions. These portions 43 and 43' also aid in guiding the hooks 39 and 40 into the eyes, keeping in mind that these hooks are attached at the back of the body of the wearer and it is important to guide the hooks accurately into the eyes to assure the coupling engagement in maintaining the garment upon the body of the wearer.

Having fully described my invention, what I claim as new and desire to secure by Letters Patent is:

1. In brassières having front breast pocket portions, wide bands extending from the ends of the pocket portions to the sides and back of the garment, shoulder straps joining the bands with the upper central portions of the pockets, end portions of the bands having upper and lower corners, a pair of substantially V-shaped strap members attached to the upper and lower corners of said bands and converging outwardly with respect to said band ends, said strap members having contracted free ends, a plurality of fastener devices attached to the central portion of each of said bands at longitudinally spaced intervals, and companion fastening devices on the contracted ends of said strap members adapted for engagement with the fasteners of said bands in adjustably coupling the strap members therewith.

2. In brassières having front breast pocket portions, bands extending from the ends of the pocket portions to the sides and back of the garment, shoulder straps joining the bands with the upper central portions of the pockets, a pair of substantially V-shaped strap members attached to free end portions of said bands and converging

outwardly with respect to said band ends, said strap members having contracted free ends, a plurality of fastener devices attached to each of said bands at longitudinally spaced intervals thereon, companion fastening devices on the contracted ends of said strap members adapted for engagement with the fasteners of said bands in adjustably coupling the strap members therewith, the V-shaped arrangement of said strap members forming openings therein, and the contracted end of one strap member being adapted to extend outwardly through the opening of the other strap member.

3. The combination with a brassière having rear wide end portions and a plurality of eyes spaced centrally and longitudinally of said end portions, of V-shaped strap members converging outwardly from upper and lower edges of said rear end portions and terminating in converging ends, said V-shaped strip members being adapted to cross and interfit at the back of the garment, and hook members on the converged ends of said strap members for adjustable coupling with the spaced eyes of an opposed rear end portion of the brassière.

JACK GLICK.
